ADHESIVE TAPE DISPENSER

Herman H. Hillmer, Omaha, Nebr., assignor to
Better Packages Incorporated, a corporation of
New York

Application August 23, 1945, Serial No. 612,258

15 Claims. (Cl. 164—42)

1

The present invention relates to the art of dispensing tape.

It is an object of the invention to provide a device for dispensing predetermined lengths of tape from a roll or coil thereof. The invention is particularly applicable to the dispensing of pressure sensitive adhesive tape which is characterized by the fact that it adheres to a material upon pressure. Tape of this character may have a normally adhesive or tacky surface upon one or both sides thereof. One well known type of such tape is that identified by the trade name "Scotch," which includes a transparent cellulose film having a coating of clingable material upon one side thereof. The invention, however, is not limited to use with that particular type of tape.

As heretofore practiced, certain devices have been employed, such as that certain device shown and described in United States Patent No. 2,221,213, the mechanism of which facilitates a manual uncoiling of a roll of the said tape and a tearing of a length of tape from a coil thereof. However, during the use of said mechanisms, an operator usually pulls out from the coil too great a length whereby a large amount of tape is wasted and the present invention aims to provide a means whereby a predetermined length only may be withdrawn from a roll of said tape, said length being sufficient for sealing oppositely disposed edges of package papers together, whereby economy is practiced in the art of sealing bundles in stores and the like.

A further object of the invention is to provide a device for conserving an operator's time in sealing packages and bundles with said special tape since, as heretofore practiced, during an operation of the mechanism of the Patent No. 2,221,213, an operator would often tear off too short a length of tape from a roll for paper sealing purposes, thereby necessitating a tearing off of a second strip with an attendant waste of time and material and the present invention aims to obviate certain other disadvantages of the prior practice.

Other and further objects and advantages of the invention will be obvious from the following detailed description thereof.

In the drawings:

Figure 1 is a side view of a tape severing and dispensing mechanism embodying the present invention.

Figure 2 is a longitudinal vertical section thereof, the view being taken substantially on line 2—2 of Figure 3.

2

Figure 3 is a top plan view of the mechanism shown in Figure 1.

Figure 4 is a side view of a portion of the new mechanism, the view being taken substantially on line 4—4 of Figure 3.

Figure 5 is a transverse vertical section of a portion of the machine and showing a tape holder roller employed, the view being taken substantially on line 5—5 of Figure 3.

Figure 6 is an end view of the mechanism shown in Figure 1.

Figure 7 is a detail showing a slideable cutter or knife employed.

Referring now to the drawings for a more particular description, 10 indicates a base and 11 a wall or plate which is secured thereto by any suitable means such as welding or the like or formed integral therewith, whereby a support or frame is provided for the later described parts. During use, the plate 11 is approximately vertically disposed since the base rests upon a counter, desk or the like. An enclosure housing, not shown, is preferably employed and the major portion of the later described mechanism is disposed therein.

The preferred embodiment of the invention shown in the drawings includes a roller for supporting a coil of tape thereon, a reel-wheel, an actuating lever, a ratchet mechanism for connecting said lever and reel-wheel together, a knife or cutter, a means for causing said knife to sever the tape during a movement of the lever in one direction and a means for restoring the position of the knife and other movable parts to a normal position with respect to the frame and each other.

Referring to Figure 5, the vertically disposed frame plate 11 is provided with a stud bolt 12, the latter being disposed at a right angle to said plate. The bolt 12 provides an axle upon which a later described tape holder or roller is revolvably disposed.

The tape holder preferably includes a sleeve 13 pivotally mounted on the axle 12. A disc 14 is axially disposed on the sleeve 13 and prevented from movement longitudinally of the sleeve by means of a collar 15, the latter being preferably provided with a set screw 16.

The disc 14 is step-cut, as indicated at 17, for providing an annular shoulder for supporting thereon a later described roll of tape.

The outer end of the sleeve 13 is provided with screw threads 18 and a second plain disc or plate 19 is threadedly engaged with the thread 18 of the sleeve 13. As thus described, it will

be seen that the plate 19 may be positioned closer toward the disc 14 or further away from said disc than is shown in Figure 5 and for purposes later described. A set-collar 20 is secured on the outer end of the bolt 12 by means of its screw 21.

A coil of the particular type of tape which the mechanism of the present invention is particularly adapted to dispense is indicated at 22. The innermost convolution of said coil is disposed about a paper core, the latter being indicated at 23. The perimeter of the core is castellated being provided with alternate notches and ridges, the latter being indicated at 24 and the notches at 25 in Figure 1, and since said core is formed of paper and castellated, the latter is compressible.

Referring to Figure 5, the inner annular wall 26 of the core 23 rests upon the annular shoulder provided by the step-cut 17 of the disc 14 and at times when the plate 19 is rotated upon the thread 18 against the core 23 of the coil, the oppositely disposed side walls of said core are squeezed between the disc 14 and the plate 19 in a manner whereby the coil of tape 22 is rigidly secured to the roller while at the same time, the tape may be unwound readily from the coil. The collar 20 prevents the plate 19 from moving away from the coil of tape 22 and the set-collar 15 positions the coil of tape and its roller longitudinally with respect to the sleeve 13.

It will be seen that a coil of tape of one-half inch width may be secured to the tape holder roller, the latter being generally indicated at 27, and that at times when it is desired to cause the machine to dispense tape from a coil of greater transverse width, the same may be readily consummated by causing the set-collar 20 and the plate 19 to be disposed further toward the free end of the axle bolt 12 than is shown in Figure 5 and complementary to the transverse width of the tape selected.

Referring to Figure 1, a second axle bolt 28 is employed having a shoulder 29 which is disposed at one side of the plate 11 and a nut 30 at the other side of said plate for drawing the shoulder 29 against the adjacent side of the plate 11, whereby the axle 28 is rigidly maintained at a right angle with respect to the plate 11 as best shown in Figure 6.

A reel-wheel 31 is revolvably disposed on the axle 28. As best shown in Figures 3 and 6, the reel-wheel is provided on the perimeter thereof with a plurality of equidistantly spaced apart fingers 32 which are radially disposed with respect to the axis of said wheel and extend from the latter at a right angle with respect to the plate 11 and transversely with respect to the roll or coil of tape 22.

The reel-wheel 31 is provided with a hub 33 which preferably is formed integral with the hub 34 of a ratchet-wheel 35. Also, if desired, the hub 33 may be locked to the hub 34 by means of a set-screw 36, as shown in Figure 6, whereby in operative effect, said hubs are integral.

As best shown in Figure 1, since the fingers 32 of the reel-wheel are disposed beyond the perimeter of said wheel, the outer edges of the fingers provide ridges indicated at 37 and the concavities 38 between said ridges for purposes later described.

The ratchet-wheel 35 is provided with a tooth for each ridge 37 of each finger 32.

It will be understood that since the said tape

is usually approximately transparent that the fingers 32 are visible through said tape as shown in the drawings.

One side of the tape is provided with a film of clingable material, said tape being known to the art as of "pressure-sensitive" type. The said material not only causes said film to adhere to said side of the tape, but also causes said film and tape to cling to substantially any extraneous substance or article with which it is placed in contact, more especially if a slight pressure be applied to said tape at that side of the latter which is oppositely disposed with respect to said film.

As thus described, it will be seen that, as shown in Figure 1, the film clings to certain of the ridges 37 of the reel-wheel during revolvable movements of the latter for unwinding the coil of tape from the core 23 since, as shown in said figure, said film is always in contact with a plurality of said fingers, whereby the amount of adhesion to said fingers is greater than the amount of adhesion of the tape to its coil.

Referring to Figure 1, since approximately five of the ridges 37 are in contact with the film of a strip of tape, the area of said five ridges or fingers being greater than the transverse width surface of a convolution of the coil 22, the latter is caused to unwind during revolvable movements of the reel-wheel since there is a greater surface for said film to cling to provided by the reel-wheel than the transverse width surface of a convolution of the coil 22.

An idler roller is preferably employed, especially in instances where tape of comparatively large transverse width is to be dispensed by the mechanism. The idler roller 38 is axially and revolvably disposed on a third axle bolt 39, the latter being disposed at a right angle with respect to the plate 11 and secured to the latter by any suitable means. The opposite ends of the idler roller 38 are respectively disposed between suitable detents such as the set-collars 40 and 41.

As thus described, it will be seen that at times when the reel-wheel is rotated in the direction of the arrow 58 that a corresponding movement is applied to the coil of tape for unwinding the latter, said tape becoming severed transversely in predetermined lengths by later described means.

The means for rotating the reel-wheel intermittently includes a lever 42 which may be provided with a handle 43 at its outer or free end. The inner end of the lever is attached by any suitable means to a carrier-plate 45 or may be formed integral with said plate.

As best shown in Figure 7, the carrier-plate 45 is revolvably disposed on the axle-bolt 28 and means are provided for limiting a swinging movement of the lever 42 in two directions, whereby the carrier-plate is reciprocably disposed on said axle-bolt 28.

As best shown in Figure 2, the carrier-plate 45 supports a pawl 46, the latter being secured to said plate by means of a pivot pin or screw 47. A spring 48 is provided having one of its ends secured to said carrier-plate by means of a screw 49 and its opposite end is disposed against the pawl adjacent the free end of the latter for urging said free end into contact with the ratchet-wheel 35 and more particularly into engagement with the teeth 50 thereof successively during revolvable movement of the ratchet-wheel in the direction of the arrow 58.

A detent or stop 51 is secured to the frame plate 11 for limiting the movement of the lever

42 toward the bobbin or roller 27 which supports the coil of tape 22 and a second detent or stop 52 is similarly secured to the frame 11 for limiting movement of said lever in an opposite direction.

As best shown in Figure 4, an end 53 of a spring 54 is secured to the carrier-plate 45 by means of a pin or other suitable keeper 55. The other end 56 of the spring 54 is similarly secured by means of a pin 57 to the frame plate 11 whereby the lever 42 is normally urged against its detent or stop 51.

At times when the lever 42 is manually moved by the operator in the direction of the arrow 58 and against the stop 52, a corresponding movement is applied to the carrier-plate 45 for causing the pawl 46 to turn or advance the ratchet-wheel 35 one or more teeth, depending upon the distance which the lever may move between the stops 51 and 52, whereby a corresponding movement is applied to the reel-wheel for advancing one or more fingers 32 or ridges 37 thereof correspondingly and for unwinding a corresponding length of tape from the coil 22. With the spacing of the stops 51 and 52 shown in the drawings, particularly Fig. 2, it will be seen that with each reciprocation of the lever the ratchet will be moved a distance of two teeth so that a piece of tape adhered to two of the fingers 32 will be severed and dispensed at each operation of the machine.

As soon as the lever 42 contacts with the detent 52, the operator releases said lever, whereupon the spring 54 returns the lever to a normal position against the detent 51 thereby causing the free end of the pawl 46 to engage the appropriate tooth 59 of the ratchet-wheel preparatory to advancing the successive fingers or ridges and by a repetition of the above described operation the device is manually actuated intermittently.

As best shown in Figure 1, a spring 59 is provided having an end secured to the base plate 10 by means of a screw or keeper 60. The free end of the spring 59 engages against the fingers 32 successively during a revolution of the reel-wheel for preventing a movement of the reel-wheel in a direction opposite to the arrow 58.

Means are provided for severing the tape during a movement of the lever 42 from its normal or full line position to the dotted line position thereof as shown in Figure 2 and said means preferably includes a knife holder 61 which is slidably disposed with respect to the carrier-plate 45 and the lever 42.

As best shown in Figure 7, the member 61 is provided with an elongated aperture 62 through which the axle bolt 28 extends.

A pin 63 is secured to one side of the knife holder 61, said pin extending through a second and similar elongated aperture 64 formed through the carrier-plate 45 adjacent the junction of the latter and the lever 42, whereby the member 61 is longitudinally slidable with respect to the lever 42 and is swingable therewith.

On that side of the knife holder 61 which is oppositely disposed with respect to the pin 63, a lug 65 is provided adjacent the end 66 of the member 61. The lug 65 carries a screw or similar suitable keeper 67 for attaching a cutter or knife 68 thereto. Preferably, as specifically shown in the drawings, a safety razor blade is employed for the cutter 68, being attached to the lug 65 by the screw 67 or in any other suitable manner.

As best shown in Figure 7, the other end 69 of

the member 61 is provided with a tang 70 which, as shown in Figure 6, is disposed at a right angle with respect to the main body portion of the member 61 and one end of a spring 71 is secured to the free end of said tang, the other end of said spring being attached to a pin 72, the latter being secured to the carrier-plate 45 and to the reverse side of the latter with respect to the member 61 as shown in Figure 4. The spring 71 normally urges the member 61 and the knife or cutter 68 toward the free end of the lever 42 whereby, as shown in Figure 1, the knife 68 is normally disposed above the strip of tape preparatory to severing the latter.

As shown in Figure 6, the cutter 68 is preferably inclinedly disposed whereby during a later described tape cutting operation, the sharp edge of the cutter traverses the strip of tape transversely and progressively during a descent of the knife and with the result that the knife does not press against the tape unduly.

During operation at times when the several parts of the mechanism are in their normal position, as shown in Figures 1 and 7, and the lever 42 is swung in the direction of the arrow 58, the knife remains in a stationary position with respect to said lever until such time as the pin 63 carried by the lever contacts with the underside of a guide-plate or cam 73 and since the latter is maintained in a stationary position, by a means later described, during a movement of the lever 42 in the direction of the arrow 58 and since, as shown in Figure 1, the guide-plate 73 is inclinedly disposed, the pin 63 is caused to become moved toward the axle bolt 28, thereby causing the knife holder 61 to become correspondingly moved together with the knife or cutter 68 and against the urge of the spring 71, whereby the knife descends from its normal position, as shown in Figure 1, through the strip of tape for severing the latter, the operation being permitted since, as shown in Figure 1, the knife is disposed between two of the spaced apart fingers 32 for a descending movement into a concavity between two of said ridges during a movement of the knife in the direction of the arrow 58.

Referring to Figure 4, the guide-plate or cam 73 is formed integral with an arm 74 and, as best shown in Figure 1, the guide-plate 73 is disposed at a right angle with respect to the main body portion of the arm 74.

One end of the arm 74 is pivotally attached to the backing plate 11 by means of a pivot pin 75.

The end 76 of the arm 74 is attached to one end of a spring 77, as best shown in Figure 2, and the other end of the spring 77, as best shown in Figure 4, is attached to the lever 42. The spring 77 urges the end 76 toward the free end of the lever 42 and its movement is limited in the said direction by means of a pin 78 which is carried by the plate 11, as best shown in Figure 3.

It will be seen that at times when the lever 42 is moved in the direction of the arrow 58 that the pin 63 engages the underside of the plate 73 for causing the knife to descend and apply a severing cut to the strip of tape since said knife is progressively forced downwardly during a swinging movement of the lever in the direction of the arrow 58.

Slightly before the lever reaches the end of its stroke and abuts the detent 52, the pin 63 disengages the underneath side of the plate 73 and the spring 71 causes the knife, together with the pin 63, to move upwardly to its initial position.

During a return of the lever to a normal position,

7
the pin 63 moves over and against the upper side of the plate 73 and the latter becomes forced downwardly against the urge of the spring 71 since the urge of the spring 54 is greater than the urge of the spring 71, whereby during operation, the pin 63 slides off of the plate 73 to its normal position, as shown in Figure 4, and travels around the plate 73 once for each succeeding cutting stroke of the knife blade 68. It will be seen that the knife is completely returned to its initial position by the action of the spring 71 before the return stroke of the lever begins, the knife passing upwardly between the cut ends of the tape. The knife thus is in position to clear the ends of the fingers 32 and the leading end of the unsevered portion of the tape, so that the oscillating lever is free to return to its initial position as soon as it is released by the hand of the operator.

During operation and assuming that the coil of tape 22 is disposed on its tape holder or roller, as shown in Figure 1, the free end 79 of the strip 80 of the coil 22 is threaded under the idler roller 36' (in instances where the latter is employed) and over a plurality of the fingers 32 and in contact with the ridges 37 of the fingers.

The lever 42 being manually moved in the direction of the arrow 58 causes the knife to descend as above described for severing the tape simultaneously with an advancement of the tape as caused by the reel-wheel, whereby a length of tape, indicated at 80, is severed from said end 79 and removably adheres to a ridge 37.

Further manipulation of the lever 42 for severing an additional length of tape causes the strip 80 to be disposed beyond the vertically disposed side edge 81 of the frame plate 11 and in an accessible position whereby the operator may dispose one of his fingers between two of the fingers 32 of the reel-wheel and under the severed length 80 for removing the latter from the ridge to which it is clinging attached during the delivery of said length to an accessible position for removal by the operator.

From the foregoing description, it is thought to be obvious that an adhesive tape dispenser constructed in accordance with my invention is particularly well adapted for use by reason of the convenience and facility with which it may be assembled and operated, and it will also be obvious that my invention is susceptible of some change and modification without departing from the principles and spirit thereof and for this reason, I do not wish to be understood as limiting myself to the precise arrangement and formation of the several parts herein shown in carrying out my invention in practice, except as claimed.

I claim:

1. In a device for cutting off preselected lengths of tape having a film of clingable material on one side thereof; a support; means for revolvably attaching a coil of said tape to said support; a member journaled to said support having approximately equidistantly spaced apart ridges thereon to which said material of said tape will detachably adhere; a cutter; a swingable lever for revolving said member and causing advance of said tape only successively and intermittently; said cutter being moved with the tape by said lever; means responsive to a swinging movement of said lever for causing said cutter to cooperate with said ridges for severing said tape between two of said ridges during a swinging movement of said lever in one direction; and means responsive to a further movement of said lever in the same

direction for returning said cutter to a normal position.

2. A device for severing predetermined lengths of tape having a film of clingable material on one side thereof comprising a roller for supporting a coil of said tape thereon, a revolvable member having a perimeter to which said material will detachably adhere, a movably mounted cutter, a lever, stops for limiting movements of said lever, a ratchet mechanism actuated by a movement of said lever for revolving said perimeter and tape with said cutter a distance proportional to a movement of said lever between said stops, means for causing said cutter to move across the path of the tape transversely to its movement with the tape and sever said tape during said movement of said lever, and resilient means for returning said cutter and lever to a normal position.

3. A device for severing a predetermined length of tape having a film of clingable material on one side thereof comprising a roller for supporting a coil of said tape thereon; a member having a surface to which said material will detachably adhere; a cutter mounted for two movements, one in a direction substantially transverse to the other; a manually movable lever; means for limiting a movement of said lever; means actuated by a movement of said lever for advancing said surface and tape a distance proportional to said limiting means; means for moving said cutter with the tape; means for causing said cutter to sever said tape responsive to said movement of said lever and means to return said cutter to its original position.

4. A device for severing predetermined lengths of tape having a film of clingable material on one side thereof comprising a roller for supporting a coil of said tape thereon; a member having fingers to which said material will detachably adhere, said fingers being approximately equidistantly spaced apart; a cutter arranged to operate between said fingers and to move with said member; manually actuatable means for causing said fingers to move with said cutter intermittently for unwinding said coil; and means for causing said cutter to move transversely of, and sever said tape once for each intermittent movement of said fingers, and means to effect a reverse movement of the cutter relatively of the tape while the latter is at rest.

5. In a tape-dispensing device, a frame, a tape-feeding member movably mounted on the frame and provided with a plurality of spaced feed surfaces, an oscillatable member having a one-way driving connection with said feed member, a cutter movably mounted on said oscillatable member, and means to move said cutter across the path of the tape on said feed surfaces to sever the tape.

6. In a tape-dispensing device, a frame, a tape-feeding member movably carried by the frame and having a plurality of spaced elements to which the tape is adapted to cling, a cutter, means for mounting said cutter on the frame for movement with said feeding member during the advance thereof and for movement across the path of the tape carried by said member, and means for advancing the feeding member intermittently.

7. In a tape-dispensing device, a frame, a tape-feeding member movably carried by the frame and having a plurality of spaced elements to which the tape is adapted to cling, a cutter, means for mounting said cutter on the frame for movement with said feeding member during the advance thereof and for movement across the

path of the tape carried by said member, means for advancing the feeding member intermittently, and means for effecting movement of the cutter across the path of the tape during the advance of the cutter with the feeding member.

8. In a tape-dispensing device, a frame, a tape-feeding member movably carried by the frame and having a plurality of spaced elements to which the tape is adapted to cling, a cutter, means for mounting said cutter on the frame for movement with said feeding member during the advance thereof and for movement across the path of the tape carried by said member, means for advancing the feeding member intermittently, and means to move the cutter across the path of the tape and back to its normal position during the advance of the cutter with the tape-feeding member.

9. In a tape-dispensing device, a frame, a tape-feeding member movably carried by the frame and having a plurality of spaced elements to which the tape is adapted to cling, a cutter, means for mounting said cutter on the frame for movement with said feeding member during the advance thereof and for movement across the path of the tape carried by said member, means for advancing the feeding member in a step-by-step movement, and means for advancing the cutter with the feeding member and moving it across the path of the tape to sever the same, means to return the cutter to its normal position, and means to effect a reverse movement of the cutter relatively to the tape when the latter is at rest to position the cutter opposite a point on the tape spaced from the severed edge thereof.

10. In a tape-dispensing machine, a frame, a tape-feeding member movably mounted on the frame and provided with a plurality of spaced feed surfaces, an oscillatable member having a one-way driving connection with said feed member, a cutter movably mounted on said oscillatable member, and means to move said cutter across the path of the tape and between said feed surfaces to sever the tape.

11. In a tape-dispensing machine, a frame, a tape-feeding member movably mounted on the frame and provided with a plurality of spaced feed surfaces, an oscillatable member having a one-way driving connection with said feed member, a cutter movably mounted on said oscillatable member, means for effecting forward and reverse movement of said oscillatable member to advance the tape-feeding member intermittently with said cutter, and means carried by the frame to effect transverse movement of the cutter across the path of the tape to sever the latter.

12. In a tape-dispensing machine, a frame, a tape-feeding member movably mounted on the frame and provided with a plurality of spaced feed surfaces, an oscillatable member having a one-way driving connection with said feed member, a cutter movably mounted on said oscillatable member, means for effecting forward and reverse movement of said oscillatable member to advance the tape-feeding member intermittently with said cutter, means carried by the frame to effect transverse movement of the cutter across the path of the tape to sever the latter, and means to effect a return movement of the cutter on said oscillatable member after the cutting operation has been performed.

13. In a tape-dispensing machine, a frame, a tape-feeding member movably mounted on the

frame and provided with a plurality of spaced feed surfaces, an oscillatable member having a one-way driving connection with said feed member, a cutter movably mounted on said oscillatable member, means for effecting forward and reverse movement of said oscillatable member to advance the tape-feeding member intermittently with said cutter, means carried by the frame to effect transverse movement of the cutter across the path of the tape to sever the latter, means to effect a return movement of the cutter on said oscillatable member after the cutting operation has been performed, and means to return said oscillatable member and cutter to their rearward positions after an advance thereof, said cutter during such movement moving rearwardly along the tape on said feeding member.

14. In a tape dispensing machine for pressure sensitive adhesive tape, a frame, a tape feeding member movably mounted on the frame and provided with a plurality of spaced adhesion surfaces, an oscillatable member having a one way driving connection with said feed member, whereby oscillations of said oscillatable member will advance said feed member intermittently, a cutter movably mounted on said oscillatable member so as to advance with said oscillatable member and feed member on the feeding movement of said oscillatable member, cam means carried by the frame, a member associated with the cutter for engaging said cam means on the feeding movement of said oscillatable member to effect movement of the cutter across the path of the tape to sever the latter, and means for returning the cutter to its initial position before the reverse movement of the oscillatable member takes place, said cam means being mounted to move out of the path of the cutter operating member upon the return movement of the oscillatable member.

15. In a tape dispensing machine for pressure sensitive adhesive tape, a frame, a tape feeding device mounted on said frame and provided with a plurality of spaced adhesion surfaces movable in an orbital path, means for intermittently advancing said feed device, a cutter, means for mounting said cutter to oscillate adjacent to said feed device, said cutter moving in synchrony with said feed device during forward movement thereof and oscillating rearwardly during the periods of rest of said feed device, means for moving the cutter across the path of the tape so as to sever the tape during the synchronous movement of said cutter and feed device, the spaces between successive adhesion surfaces being sufficiently deep to permit the cutter to pass entirely through the tape into said spaces, and means for moving the cutter out of the space between successive adhesion surfaces and between the severed ends of the tape before the return oscillation of the cutter takes place.
